UNITED STATES PATENT OFFICE.

MOSES M. MOORE, OF CHICAGO HEIGHTS, ILLINOIS, ASSIGNOR TO THE
Q & C COMPANY, OF CHICAGO, ILLINOIS.

DRILL.

SPECIFICATION forming part of Letters Patent No. 634,502, dated October 10, 1899.

Application filed December 22, 1898. Serial No. 700,002. (No model.)

To all whom it may concern:

Be it known that I, MOSES M. MOORE, a citizen of the United States, residing at Chicago Heights, in the county of Cook and State of

Illinois, have invented certain new and useful Improvements in Drills; and I hereby declare the following to be a full, clear, and exact description of the same, reference being had to the accompanying drawings, in which—

10 Figure 1 is a side elevation of drilling appliances embodying my invention, parts broken away and the drill withdrawn. Fig. 2 is a plan view of the drill appliances, the vertical shaft, its miter-gear, and its bridge or base-plate being removed to more clearly show the connection between the feed-screw and drill-spindle, the miter-gear and the cam and lever which actuate the nut of the feed-screw being indicated in dotted lines.

20 In this figure the drill is shown in its advanced position, having passed through the web of a rail, and the devices for automatically withdrawing the drill are shown as in engagement with the spur-gears of the spindle miter-gear and the feed-nut. Fig. 3 is an enlarged detached longitudinal section of the drill-spindle and its miter-gear and spur-gear, the feed-screw, its feed-nut and spur-gear, and the shifting rod or shaft and pinions,

25 whereby the miter-gear of the spindle and the feed-nut are coupled or connected for automatically and rapidly advancing or withdrawing the drill; and Fig. 4 is a transverse section of the devices, taken on the line 4 4;

35 Fig. 2. Like symbols refer to like parts wherever they occur.

My invention relates generally to portable drilling apparatus, and has been especially devised for use as a "rail-drill" for drilling the webs of rails when in position in the track, but is not to be taken as limited thereto, as certain features of construction will be found of general utility in this class of apparatus.

45 The main objects in view are, first, the provision of means for rapidly and automatically withdrawing or advancing the drill when it becomes necessary to advance it to or withdraw it from the rail-web or other article operated upon, and, second, the provision of a simple and efficient coupling between the

rotatable drill-spindle and non-rotatable feed-screw which will insure the control of the longitudinal or endwise movement of the spindle by the feed-screw without interference with the rotation of the spindle. 55

In order to secure the first of the above-noted objects, I combine with the gearing which actuates the drill-spindle and the feed-screw thereof an endwise-movable shaft having an attached pinion and a pinion through which the shaft moves, the latter pinion being in constant gear with the feed-nut, whereby the feed-screw may be actuated from and simultaneously with the drill-spindle, and 60 such a combination or its equivalent embodies one feature of my invention.

In order to secure the second object above noted, I combine the drill-spindle and feed-screw by means of a shell or box, a detachable collar or plug, and an interposed ball-race and balls, whereby an antifriction end bearing between the parts is provided and a close connection of the spindle and feed-screw for purposes of longitudinal movement is obtained, and such a combination or 75 its equivalent embodies another feature of my invention.

There are other minor features of invention, all as will hereinafter more fully appear. 80

I will now proceed to describe my invention more fully, so that others skilled in the art to which it appertains may apply the same.

In the drawings, A indicates the main frame 85 for the support of the operative mechanism, said frame having at its front end lateral guide-lugs a a, through which pass links B B, that carry the pivoted clamp-hooks b b, and having journaled at its rear a shaft C, provided at its ends with crank-pins c c, with which the links B B are connected. The shaft C is also provided with a lever or handle c', whereby it may be rocked to advance or retract and lock the links B B and 95 hooks b b.

Journaled in the front bar of frame A is the miter-gear D of drill-spindle E, and said miter-gear is provided with a spur-gear d, while at the rear of the frame and in axial line with miter-gear D is the feed-nut F of feed-screw G, said feed-nut F also provided

with a spur-gear f , the counterpart of that upon the miter-gear of the drill-spindle.

E indicates the drill-spindle, provided with a keyway e (see Fig. 3) for the reception of a key d' or spline in the hub of the miter-gear D, whereby the drill-spindle is caused to rotate with the miter-gear D, though capable of endwise movement independently of the miter-gear.

10 G indicates the feed-screw for the drill-spindle E, to which the feed-nut F imparts an endwise motion, the feed-screw being secured against rotation, as will hereinafter appear.

15 Secured to the end of feed-screw G by a pin g or in other suitable manner is a shell or box H, threaded, as at h , for the reception of a threaded annular plug or collar I, which loosely surrounds the adjacent end of drill-spindle E, and fitted closely within the box H and bearing on the end of feed-screw G is a hardened disk g' , grooved to form a raceway for antifriction-balls g^2 , while the adjacent end of drill-spindle E is capped by

20 a hardened disk e' , secured thereto by a screw e^2 or in other suitable manner and projecting beyond the drill-spindle, so that the spindle shall be confined to the box H by means of the annular plug I, though capable of rotation within said plug. In fitting up the parts the loose annular screw-plug I will be passed over the drill-spindle shaft before the hardened disk e' is secured to said spindle.

K indicates a cross-bar or saddle arranged 35 to slide longitudinally within the frame A upon ways or guides k , and to said saddle or cross-bar the box or shell H is secured by screws k' or in other suitable manner, so that the box k and feed-screw H are prevented 40 from rotating, while the free endwise movement of the feed-screw F is not interfered with.

L indicates a removable cap-plate or bridge (see Fig. 1) which spans the frame A, is supported thereon and secured thereto, and which cap-plate or bridge carries a vertical tube l , in which is journaled the shaft M for applying the power to rotate the drill-spindle. Shaft M is provided above (see Fig. 1) with 50 a miter-gear M' , with which engages a miter-gear N' on the shaft N and below with a miter-gear M^2 , which meshes with the miter-gear D of the drill-spindle and in addition thereto is provided with a cam (see dotted lines, Fig. 2) which through the medium of a lever O, pivoted on the frame A, and a spring pawl or dog o actuates the feed-nut F of the feed-screw G. The shaft N, which carries the miter-gear N' , is journaled in a yoke or 55 bracket n , supported on the upper end of tube l , and said shaft may be provided with the usual crank-handle commonly used for rotating such a shaft.

60 Journalized on the frame A, at one side thereof, (see Figs. 2 and 3,) is a shaft P, provided at one end with a knob P' and capable of endwise movement in its bearings. This shaft

P is provided at one end with a pinion p , secured thereto by a pin p' or in other suitable manner which will insure the movement of said pinion endwise with the shaft, and at its opposite end with pinion p^2 , provided with a key or spline p^3 , which travels in a keyway p^4 of the shaft P, so that said second pinion will rotate with the shaft P, but will permit the shaft to move endwise through said pinion. The first-noted pinion p is adapted to mesh with spur-gear d of miter-gear D when the shaft P is pushed forward and to be disengaged therefrom when the rod or shaft P is pulled back, while the second pinion p^2 remains in permanent mesh with the spur-gear f of feed-screw F, being located between two bearings or other suitable provision to accomplish the same being made.

85 The construction of the devices being substantially of the character hereinbefore pointed out, their operation will be as follows: Assuming the drill to be withdrawn and the parts in the position shown with relation to a track-rail—that is to say, the clamp-hooks b passed over the rail and bearing upon the web thereof, which has been accomplished by throwing the lever c' forward into the position shown in Fig. 1, so as to rotate the crank-shaft C c and retract the links B B, which carry the pivoted clamp-hooks b —the shaft N is rotated by means of a suitable crank-handle and through miter-gears $N' M'$, shaft M, miter-gears M^2 and D rotates the drill-spindle E. At the same time the cam (see dotted line, Fig. 2) actuates lever O, which through the medium of dog or pawl o rotates the feed-nut F and (as the feed-screw is fixed against rotation) causes the endwise movement of the feed-screw G and the advance of the drill-spindle E and its drill. During the foregoing or drilling operation of the appliances the rod or shaft P has been drawn back, (see Fig. 3,) so that pinion p is out of mesh with the spur-gear d on miter-gear D; but as soon as the drilling operation is finished the operator first lifts the dog o of lever O out of engagement with feed-nut F and then pushes the shaft or rod P forward (see Fig. 2) until the pinion p meshes with spur-gear d , whereupon a rapid reverse rotary motion is imparted from miter-gear D, through its spur-gear d , pinion p , shaft P, and pinion p^2 , to spur-gear f on feed-nut F, and feed-screw G is rapidly withdrawn, carrying with it the drill-spindle, which, as before noted, has an endwise movement through its miter-gear D. It is desirable to completely free the drill from its work (the track-rail) before the withdrawal movement is arrested, after which the drill can be rapidly advanced to its work by the reverse motion of the shaft N as preliminary to the next drilling operation, after which the dog o of lever O is replaced in engagement with feed-nut F, and the drilling operation and slow feed of the drill-spindle will proceed as before.

Having thus described my invention, what

I claim, and desire to secure by Letters Patent, is—

1. In a drill, the combination of a main frame, driving-gear journaled on the main frame, a drill-spindle rotatable with and movable endwise through the driving-gear, a feed-nut, a feed-screw coupled to the drill-spindle, and a saddle or slide movable on the main frame and which carries the feed-screw, substantially as and for the purposes specified.
2. In a drill, the combination with a main frame, a driving-gear journaled thereon, a drill-spindle movable with and through the driving-gear, a feed-nut, a feed-screw, a saddle or slide movable on the main frame and with which the feed-screw is connected, and an antifriction ball-bearing interposed between the drill-spindle and feed-screw, substantially as and for the purposes specified.
3. In a drill, the combination of a main frame, a driving-gear and a pinion journaled thereon, a drill-spindle movable with and through said driving-gear and pinion, a feed-

nut and pinion, a feed-screw, a saddle or slide movable on the main frame and with which the feed-screw is connected, a sliding shaft having an attached pinion and a loose pinion, the latter being in constant gear with the pinion of the feed-nut and the former adapted to engage the pinion of the driving-gear, substantially as and for the purposes specified.

4. In a drill, the combination with a drill-spindle and its feed-screw of interposed hardened disks one of said disks attached to the drill-spindle, and a coupling-box and annular plug for connecting the drill-spindle with the feed-screw, substantially as and for the purposes specified.

In testimony whereof I affix my signature, in presence of two witnesses, this 16th day of December, 1898.

MOSES M. MOORE.
